AUTOMATIC LOCK

Frederik J. Borup, Stratford, Conn.

Application February 6, 1951, Serial No. 209,626

10 Claims. (Cl. 292—332)

1

This invention relates to new and useful improvements in locks and has particular relation to a closure actuated lock for automatically locking a closure in closed position on the latter being moved from open to closed position.

An object of the invention is to provide a self-locking or automatic lock of simple yet rugged structure, which is reliable in use and adapted for long, useful life and may be manufactured at reasonable cost.

Another object is to provide an automatic lock including several features of construction whereby on being actuated to released position it will remain in such position even though the closure is not opened or until the operator is ready to move the closure to open position, which can be manually moved following its automatic locking to draw together the sashes of a window when used as a window lock or to draw more tightly closed another type of closure, which cannot be tampered with from the outside of the closure and will resist all efforts to open the closure, and which is easily installed even by unskilled persons.

Another object is to provide a self-locking or automatic lock for the sashes of a double hung window.

Other objects and advantages of the invention will become apparent from a consideration of the following detailed description taken in connection with the accompanying drawing wherein a satisfactory embodiment of the invention is shown. However, it is to be understood that the invention is not limited to the details disclosed but includes all such variations and modifications as fall within the spirit of the invention and the scope of the appended claims.

In the drawing:

Fig. 1 is a sectional view through the meeting rails and adjacent portions of the top and bottom sashes of a double hung window and showing my improved lock in place thereon and with the bottom sash raised and the lock mount cut away on one side to show the mechanism;

Fig. 2 is a similar view but with the sashes closed and the lock locked;

Fig. 3 is a view similar to Fig. 2 but with the lock released whereby the sashes may be opened or moved relatively; and

Fig. 4 is a top plan view of the lock on portions of the meeting rails of the sashes of a double hung window.

Referring in detail to the drawing, at 10 is generally indicated the lower portion of the top sash of a double hung window and at 11 is generally

indicated the upper portion of the bottom sash of such window. Thus, in the sash portions 10 and 11 are shown the meeting rails 12 and 13 comprising respectively the bottom rail of the top sash 10 and the top rail of the bottom sash 11. My improved lock, generally designated 14, is mounted on the mentioned meeting rails and comprises a keeper part generally designated 15 and a latch part generally designated 16, such parts being mounted on the rails 12 and 13, respectively.

Keeper part 15 comprises a base or mounting portion 17 through which is passed screws or other fasteners 18 for securing the base against the upper side of the rail 12. Rigid with and actually shown as integral with said base is an upstanding post 19 cut out through its front face whereby it comprises a hook portion 20 having an inclined under surface 21 located at a rather acute angle to an inclined front face 22. Further, it is noted that the forward surface 23 of the hook 20 is rearwardly of the forward face 24 of the base 17.

Such base has a channel 25 through the mid portion of its under side and extending from front to back. Channel 25 receives the connecting portion of a trip device comprising a flat spring including a relatively long front arm 26, a connecting portion 27 passing under the base 17, and a rear arm 28. The front and rear arms 26 and 28 bear against vertical portions of the base or of the keeper portion thereof and it will be seen that the spring passing through the channel 25 is held in position when the keeper part 15 is mounted on rail 12. Here it is noted that the spring arm 26 extends upwardly partly across the front side of the cutout or undercut opening in the post 19 and has its upper end portion 29 rearwardly offset at a steep incline. The purpose of this tripping device comprising the described spring will be fully set forth.

The lock part 16 comprises a body 30 including lateral portions through which may be passed screws or other fasteners 31 for mounting the body on the upper side of rail 13 whereby to be in line with and adjacent the keeper part 15 when the top and bottom sashes 10 and 11 are both closed. Body 30 is shown as provided with a pair of upstanding ears 32 and 33 arranged in spaced relation. Between the ears 32 and 33, body 30 includes an outer arcuate surface portion 34 terminating in a shoulder 35 beyond which is an inner arcuate surface portion 36 terminating at one edge of an upper surface or shoulder 37.

A pin 38 passing through one end portion, spe-

cifically the upper or inner end portion of a latch 39, pivotally mounts said latch for swinging movement as will be described. At its other end portion, latch 39 is offset or provided with a toe or hook 40 adapted to cooperate with the hook 29 of the keeper by engaging the under surface of the latter for the locking of the sashes closed, as in Fig. 2. For the purpose of later description, the heel portion of the latch 39 rearwardly of the toe 40, is here designated 41 and in the released or set position of the latch, such portion 41 is against the stop or limiting shoulder 35 whereby the set or released position of the latch is a predetermined position.

A hand lever, generally designated 42 and somewhat in the form of an inverted T, includes a handle 43 and arms 44 and 45 at the inner ends of said handle and extending in substantially opposite directions therefrom. Arm 44 is bifurcated and straddles or receives in its bifurcation a web 46 formed integral with an intermediate portion of the latch 39 and a pivot pin 47 passing through these overlapped parts pivotally connects said arm 44 and thus the entire hand lever with the latch.

When the parts 15 and 16 are mounted on the rails 12 and 13, they are mounted adjacent the opposed edges of said rails and in alignment and the latter is readily accomplished by aligning the fastening screws 18 of the keeper part with the fastening screws 31 of the latch part. When the lock is unlocked, the parts are related as in Fig. 1, i. e., the spring arm 26 is in a substantially vertical position, the latch portion 41 is against the stop or shoulder 35 of the mounting element, and the forward portion of the toe 40 of the latch is projecting inwardly or forwardly over the innermost edge of the base 30 of the mounting element.

Additionally, the underside of the arm 45 of hand lever 42 is resting against the surface or shoulder 37 of the base. In this relation of the parts, the projected portion of toe 40 is so located that on a closing movement of the sashes, or of one sash relative to the other, such projecting portion of the toe will clear the front face 23 of the hook 20 but will engage the inclined top surface of the upper end portion 29 of the spring arm 26.

The relative movement of the sashes, i. e., the movement of either sash to closed relation with respect to the other, brings about the engagement of the projecting portion of the toe 40 with the spring arm 26. As a result, there is a tendency to lift the latch 39 through an arcuate movement, the center of which is the pivot pin 38. Thus, as the latch is lifted, its toe is swung inwardly and is pressing against the spring arm 26 and enters under the hook 20 of the keeper so that the upper inclined surface of the toe engages the under inclined surface 21 of the hook 20 whereby the latch and keeper are tightly engaged.

The same described swinging movement of the latch results in a drawing forwardly, as well as a slight raising, of the arm 44 and thus of the arm 45 of the hand lever 42 so that the arm 45 is drawn forwardly off the surface or shoulder 37. Then the weight of the handle 43 causes a gravitational swinging of the entire hand lever 42 on the pivot 47 whereby the hand lever moves to the position in Fig. 2. There it will be seen that the end surface of the hand lever arm 45 is now against the arcuate surface 36 above mentioned. Thus, the hand lever is locked against swinging movement with latch 39 in a clockwise direction about pivot pin 38 and arm portions 44 and 45

constitute a strut retaining the latch 39 against such movement. Surface 36 is in eccentric relation to the pivot 47 when the latter is located as in Fig. 2. That is the portion of said surface 5 adjacent stop 35 is closer to the pivot than is the portion of said surface adjacent shoulder 37. Therefore, downward pressure on the handle thrusts upwardly through the strut 44—45 on the latch 39. If the sashes cannot move relatively vertically they are drawn into relation with their meeting rails tight together by engagement of the inclined surface 21 of the keeper acting with the upper inclined surface of the toe 40.

Movement of the latch in a counter clockwise direction is prevented by its interlocking with the keeper hook 20. Thus it will be seen that the latch 39 is rigidly held in the position in which it is shown in Fig. 2. With the latch engaging the keeper hook the bottom sash 11 cannot be raised and the top sash cannot be lowered. Therefore, the sashes are locked in their closed positions. This locking is accomplished automatically and thus a householder or the like closes the sashes and automatically locks them and can not forget to lock them.

When the lock is released handle 43 is used to manipulate it and swing it as from the position of Fig. 2 to the dotted line position of Fig. 3, thus drawing the latch in a clockwise direction about the pivot 38 and withdrawing the toe 40 of the latch from locking engagement with hook of the keeper. This movement brings the heel portion 41 of the latch against stop 35 and carries the arm 45 of hand lever 42 upwardly above the arcuate surface 36 and above the shoulder or stop 37 as the hand lever moves rearwardly on the described clockwise movement of the latch. Then the operator may release the hand lever and it will, by gravity, drop to the full line position of Fig. 3 without causing any movement of the latch which it will be seen is still deflecting the spring arm 26 to some extent.

Now, when one of the sashes is moved relative to the other, as into the relationship of Fig. 1, the engagement of the arm 45 of the hand lever with the shoulder 37 prevents the hand lever from gravitating about either its pivot pin 47 or the pivot pin 38 of the latch and so the overbalancing effect of the handle 43 on the hand lever cannot cause movement of the latch from its set or released position with its heel portion 41 engaging the stop 35. Therefore, the latch is accurately positioned in a predetermined location to again be deflected by the spring arm 26 into locking relation with the keeper on the sashes being closed by movement of either one of them.

Having thus set forth the nature of my invention, what I claim is:

1. In a lock, a keeper comprising a post including a base or mounting portion and an outer portion the front edge of which is located rearwardly of the front face of said base, said outer portion undercut whereby it comprises a hook portion the under surface of which inclines inwardly and upwardly of the post, a latch for cooperation with said keeper and comprising a mounting member, a latch pivoted at one end to said mounting and at its other end including a toe inclined on its upper side and adapted to enter under the hook of said keeper with the inclined side of the toe engaging the inclined surface of the keeper, a hand lever including a handle and an arm, said arm pivoted to said latch intermediate the ends of the latter for shifting thereof, said handle overbalancing said hand lever and normally tend-

ing to shift the same to shift said latch to locking position, and a shoulder on said mounting member and releasably holding said hand lever against such movement.

2. In a lock, a keeper part, a latch part comprising a latch adapted to lock with said keeper, a mounting member, means pivoting said latch on said mounting member for pivotal movement between a set position free of said keeper and a locked position engaging said keeper, hand lever for shifting said latch from said locked to said set position, a trip means for shifting said latch from said set to said locked position on movement of one of said parts in a plane parallel with but to pass the other, said hand lever being pivotally mounted and normally under the influence of gravity to move said latch from the first mentioned to the second mentioned of said positions, and a shoulder on said mounting in the path of movement of said hand lever when the latch is in set position to restrain such movement of said hand lever under the influence of gravity.

3. A closure lock comprising a keeper part and a latch part adapted one to be mounted on a closure for movement therewith relative to the other as the closure is moved between closed and open positions, said keeper part comprising a post having a hook portion, said latch part comprising a mounting means, a latch pivoted on said mounting means for swinging movement between a locked position engaging the hook portion of said keeper and a released position free thereof for relative movement of the lock parts, means on said mounting for engaging and limiting swinging movement of said latch to the last named position whereby the latter is a predetermined position, and a spring on said keeper part and positioned to engage said latch and direct it into locking engagement with the hook portion of said keeper post on movement of said closure to closed position.

4. A closure lock comprising a keeper part and a latch part adapted one to be mounted on a closure for movement therewith relative to the other as the closure is moved between closed and open positions, said keeper part comprising a post having a hook portion, said latch part comprising a mounting means, a latch pivoted on said mounting means for swinging movement between a locked position engaging the hook portion of said keeper and a released position free thereof for relative movement of the lock parts, means on said mounting for engaging and limiting swinging movement of said latch to the last named position whereby the latter is a predetermined position, a spring on said keeper part and positioned to engage said latch and direct it into locking engagement with the hook portion of said keeper post on movement of said closure to closed position, a hand lever pivoted to said latch intermediate the ends of the latter and operable to swing said latch to said released position free of said hook portion of the keeper part, said hand lever including a handle located laterally of the pivotal connection of the lever with said latch whereby said hand lever is constantly tending to gravitate to a position carrying said latch about its pivot from its predetermined released position, means on said mounting and positioned to engage said hand lever and prevent such gravitational movement thereof, and said last means having a fixed location whereby on shifting of said latch on engagement with said spring said hand lever is bodily shifted for movement in a path free of said means.

5. An automatic lock for the sashes of a double hung window, a keeper part and a latch part to be mounted on the meeting rails of the sashes of such a window, said keeper part to be fixed to the upper side of the meeting rail of a top sash and comprising a post having a hook portion, said latch part to be mounted on the upper side of the meeting rail of the bottom sash of such a window and including a mounting member, a latch pivoted at one end to said member and at its other end having a toe to engage under the hook portion of said keeper to lock said sashes in closed relation, a handle on said latch part for swinging said latch from locked position to a predetermined released position, a shoulder on said mounting member in the path of swinging movement of said latch to released position and limiting such swinging movement to that necessary to move the latch to said predetermined position, and a spring anchored to said keeper part and normally located in a position to engage the underside of the toe of said latch and swing the latter on its pivotal mounting and direct said toe under and into locking engagement with the hook of the keeper on movement of one of said sashes to closed position when the other is in closed position.

6. The automatic lock as in claim 5 including a hand lever for shifting said latch from locking position to said predetermined released position, and said hand lever including a portion pivotally connected with said latch at one end and at its other end bearing against said mounting member when the latch is in locking engagement with the keeper hook and constituting a strut for rigidly holding said latch in such position.

7. In a lock including a keeper part and a latch part, said latch part including a mounting comprising a base and an upstanding wall, a latch pivoted on said wall for swinging movement from a locked engagement with said keeper part to a released position, said base including an upper surface including an arcuate portion along which said latch may swing and a shoulder at the inner end of said portion in the path of swinging movement of the latch from locked position whereby said latch has a predetermined released position, and a hand lever for moving said latch to said released position.

8. In a lock including a keeper part and a latch part, said latch part including a mounting comprising a base and an upstanding wall, a latch pivoted on said wall for swinging movement from a locked engagement with said keeper part to a released position, said base including an upper surface including an arcuate portion along which said latch may swing and a shoulder at the inner end of said portion in the path of swinging movement of the latch from locked position whereby said latch has a predetermined released position, a hand lever for moving said latch on its pivot to said released position, means associated with the keeper part and located to be engaged by said latch when the latter is in released position and one of said parts is moved with a closure to a closed position of the latter to rock said latch on its pivot into locking engagement with said keeper; said hand lever being pivoted to said latch and movable therewith as the latter is moved to locking relation with said keeper, said upper surface of the base including a second arcuate portion along which said hand lever moves as the latch is moved into locking relation with the keeper, and said hand lever including a portion to engage said surface and function as a

strut maintaining said latch in locked relation with said keeper.

9. In a lock including a keeper part and a latch part including a mounting and a latch pivoted on said mounting and swingable between locking engagement with said keeper and a predetermined released position, a hand lever for swinging said latch to released position, said hand lever including a strut portion, and said mounting having a concave arcuate surface portion against which said strut portion engages and along which it moves as said latch moves for maintaining said latch in locking engagement with said keeper.

10. The device as in claim 8 wherein said second arcuate surface is eccentric to the pivot of said hand lever when said latch is engaging said

keeper whereby further movement of the hand lever in the same direction is a wedging action operating through said strut on said latch.
